DESIGN FOR A BOOK COVER OR SIMILAR ARTICLE

Clarence D. Trussell, Poughkeepsie, N. Y., assignor to Trussell Manufacturing Company, Poughkeepsie, N. Y., a corporation of New York

Application October 19, 1939, Serial No. 87,720

Term of patent 14 years

To all whom it may concern:

Be it known that I, Clarence D. Trussell, a citizen of the United States, residing at Poughkeepsie, Dutchess County and State of New York, have invented a new, original, and ornamental design for a Book Cover or Similar Article, of which the following is a specification, reference being had to the accompanying drawing, forming part thereof.

Fig. 1 is a plan view of a book cover embodying my new design.

Fig. 2 is an enlarged cross-sectional view as in the line 2—2 of Fig. 1.

The dominant feature of the design resides in the ornamentation applied to the corners of the book cover as shown and, while shown applied to a book cover, it is to be understood that it may be applied to other similar articles.

I claim:

The ornamental design for a book cover or similar article, substantially as shown and described.

CLARENCE D. TRUSSELL.
